UNITED STATES PATENT OFFICE.

MICHAEL LEININGER, OF CHICAGO, ILLINOIS.

WELL-MACHINE.

No. 839,773.

Specification of Letters Patent.

Patented Dec. 25, 1906.

Application filed January 11, 1905. Serial No. 240,635.

To all whom it may concern:

Be it known that I, MICHAEL LEININGER, a citizen of the United States of America, and a resident of Chicago, Cook county, Illinois, have invented a certain new and useful Improvement in Well-Machines, of which the following is a specification.

My invention relates to well-making machinery of that particular character in which the drill or tool for drilling is attached to the lower end of the rope or cable and in which means are provided for alternately drawing the tool up a proper distance and then allowing it to fall, so as to produce a vertical reciprocation, so to speak, of the said tool and in which also there are suitable means for paying out the rope or cable as fast as the work progresses and the depth of the well increases.

Generally stated, the object of my invention is to provide an improved, simplified, and highly-efficient well-machine of the foregoing general character.

A special object is to provide an improved arrangement for operating the rope or cable—that is to say, for reciprocating the tool which is employed in drilling the well.

Another object is to provide an improved arrangement for paying out the rope or cable, and thus gradually lowering the tool as the work progresses and the depth of the well increases.

A further object is to provide improved means for varying the length of the stroke of the tool.

An additional object is to provide an improved construction and arrangement for hoisting or drawing up the tool from the bottom of the well.

It is also an object, of course, to provide certain details and features of improvement tending to increase the general efficiency and serviceability of a well-machine of this particular character.

To the foregoing and other useful ends my invention consists in matters hereinafter set forth and claimed.

The single figure of the accompanying drawing is a perspective of a well-machine embodying the principles of my invention.

As thus illustrated, power is communicated to the drive-shaft A by means of a pulley B. The pinion C, which is mounted on a spline or feather upon the shaft A, engages the gear-wheel D. This gear-wheel is in turn mounted upon a crank-shaft E, provided

with a crank-arm F, the latter serving as a tripper. The rope or cable 1 for drilling the well is operated by a tripper-block G, secured to the free or up-and-down swinging end portion of the arm H, the latter being mounted upon a horizontally-disposed shaft I. An arm J, provided with a sheave K, adapted to bear down upon the said rope or cable, is secured to the forward end of the arm H. As shown, the roller or knob L slips off from the said tripper-block G, and the rope or cable is thereby released and the tool allowed to fall and strike the desired blow.

The length of stroke of the tool can be varied by moving the roller or knob L toward or away from the end of the crank-arm F, and the same effect can be obtained by varying the length of the chain 2 by means of a pin M, so as to limit the upstroke of the arm H. It will be seen that this chain connects the said arm H with the frame of the machine. The said rope or cable 1 is wound upon a drum N, adapted to rotate upon a vertical axis. A horizontally-disposed shaft O is provided with a pinion P, adapted to engage a gear-wheel Q, carried by the said drum. Said shaft O is also provided with a band-brake device R, arranged to be operated by a hand-lever S. By releasing this brake the rope or cable can be paid out at the desired rate of speed. As illustrated, the rope or cable can be wound up and the tool hoisted out of the well by means of a crank T, secured to the shaft O, or, if desired, the pinion C can be disengaged from the gear D by means of a shifter device U. After this the sprocket-wheel V can be made to rotate with the shaft A by closing the clutch W by means of the hand-lever. The sprocket-wheel V is, it will be seen, connected by a sprocket-chain with the sprocket Y on the shaft O. In this way the power can be disconnected from the tripper and then connection made with the shaft O, so that the power can be employed for winding in the rope or cable and hoisting the tool out of the well. From the foregoing it will be seen that I provide a simple and highly-improved construction of well-machines, comprising comparatively simple and effective devices for operating and controlling the drill or tool.

What I claim as my invention is—

1. A well-machine comprising a rope or cable for reciprocating the tool, means for operating said rope or cable, a drum mounted to rotate upon a vertical axis and having

- an end portion of said rope or cable wound thereon, a horizontally-disposed shaft, provided with gear connection with the base of said drum, a band-brake applied to and adapted for controlling the rotation of said shaft, and a hand-lever suitably connected for operating said band-brake, whereby said rope or cable may be paid out at will and as fast as the depth of the well increases. 40
10. 2. In a well - machine, the combination with a rotary drum, of a cable wound upon said drum, a pivotally-attached arm, a sheave attached thereto adapted to bear upon said cable, a drive-shaft provided with a pinion, a gear-wheel engaging therewith, a 45 tripper-arm, a roller adjustably mounted thereon, a tripper-block mounted on said pivotally-attached arm, and means for limiting the movement of said arm. 50
20. 3. In a well - machine, the combination with the drum N, a cable wound thereon, a pivotal arm H carrying a sheave K adapted to bear upon said cable, a crank-shaft E provided with a gear-wheel D and a crank-arm F 55 and a tripper-block G, said crank-arm being adapted to engage and release the arm H through the medium of the tripper-block G. 60
4. In a well - machine, the combination with the drum N, a cable wound thereon, a pivotal arm H carrying a sheave K adapted to bear upon said cable, a crank-shaft E provided with a gear-wheel D and a crank-arm F and a tripper-block G, said crank-arm being adapted to engage and release the arm H 65 through the medium of the tripper-block G. 70
30. 35. the movement of said drum N being regulated through the medium of a brake-lever S, and the movement of the crank-arm F being
- regulated through the medium of the shaft A and pinions C. 75
5. In a well-machine, the combination with the drum N, a cable wound thereon, a pivotal arm H carrying an upwardly-extending arm J on which is mounted a sheave K adapted to bear upon said cable, a crank-shaft E provided with a gear-wheel D and a crank-arm F and a tripper-block G, said crank-arm being adapted to engage and release the arm H through the medium of the tripper-block G, a brake-lever S, a shaft A and pinions C, the movement of said drum N being regulated through the medium of the brake-lever S, and the movement of the crank-arm F being regulated through the medium of the shaft A and pinions C. 80
6. In a well-machine, the combination of a frame, a drum N, a vertical cable attached thereto, a horizontal rotary shaft A, a horizontal crank-shaft E, gearing C and D forming a connection between said shafts, a horizontal shaft O, brake means provided therefor, and a pinion adapted to engage the gear on the drum N, an arm H carrying a sheave K and cable held in place by said sheave, dropping mechanism, the movement of said drum being regulated by the braking means secured to the shaft O, and the dropping mechanism being regulated by the movement of the shaft A. 85

Signed by me at Chicago, Cook county, Illinois, this 28th day of November, 1904.

MICHAEL LEININGER.
